UNITED STATES PATENT OFFICE.

RONALD A. McCANN, OF NEW BRUNSWICK, NEW JERSEY, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

1,197,749.

Specification of Letters Patent. Patented Sept. 12, 1916.

Application filed October 31, 1912. Serial No. 728,759.

To all whom it may concern:

Be it known that I, RONALD A. McCANN, a citizen of the United States, residing at New Brunswick, in the county of Middlesex 5 and State of New Jersey, have invented certain new and useful Improvements in Railway Signaling, of which the following is a specification.

My invention relates to signaling for single track over which traffic moves in both directions; it is particularly adapted to signaling for stretches of single track between passing sidings, although it is not limited to this particular adaptation.

I will describe one form of railway signaling embodying my invention, and will then point out the novel features thereof in claims.

In the accompanying drawings Figure 1 20 is a diagrammatic view showing a stretch of single track having applied thereto one form of railway signaling embodying my invention. Figs. 2, 3, 4 and 5 are views similar to Fig. 1, showing the effect on the 25 apparatus and circuits of the passage of a car or train through the stretch.

Similar reference characters refer to similar parts in each of the several views.

Referring to the drawings, A is a stretch 30 of single track between two passing sidings B and C. The stretch A is provided with one or more track circuits; as here shown it is provided with two track circuits each of which comprises a track battery 10 and a track relay T or T'. Extending in each direction from the stretch A are preliminary track circuits p and p' each of which includes a track battery 10, and a track relay P or P'.

S is a signal device governing traffic through the stretch A from west to east, and S' is a similar signal device governing traffic through the stretch A from east to west. Each of these signal devices as here shown 45 comprises two semaphore arms 11 and 12; when both arms are horizontal the signal indicates "stop"; when arm 11 is inclined the signal device indicates "clear"; when the arm 11 is horizontal and the arm 12 is inclined, the signal device indicates "caution".

Operatively connected with semaphore arm 11 of each signal device are two circuit controlling contacts 42 and 51; when the arm 11 is horizontal, contact 42 is open and 55 contact 51 is closed, and when arm 11 is in-

clined, these contacts are respectively closed and open. Operatively connected with each of the track switches 61 and 61^a leading from the stretch A into the sidings B and C is a circuit controlling contact 41 or 41^a 60 which contact is closed when the switch is set for straight traffic on the main track, and is open when the switch is set for traffic into or out of the siding.

The clear indication of each signal device 65 is controlled by means of a polarized relay H or H' and the caution indication of each signal device is controlled by means of a neutral relay L or L'. The control circuits for the signal devices will be traced herein- 70 after in explaining the operation of the system.

R and R' are auxiliary relays whose functions will appear hereinafter.

The operation of the system is as follows: 75 Assume that a car or train moving from east to west enters the preliminary track circuit P' as shown in Fig. 2. Track relay P' opens, and its back contact 24 closes the following circuit—from battery D' through 80 wires 48 and 21, contact 22 of relay R', wire 23, contact 24, wires 25 and 26, winding of polarized relay H', wire 27, contact 28 of relay T', line wire 29, contact 28 of relay T, wire 70, winding of polarized relay H, wires 85 71 and 72, contact 24 of relay P, wires 30 and 20, common wire O to battery D'. This circuit I will hereinafter refer to as the "line" circuit. The current in this circuit is in such direction as to reverse the polarized armature 16 of relay H' but not to reverse the polarized armature 38 of relay H, but the neutral armatures of both of these relays are of course closed. The reversal 90 of polarized armature 16 and closure of neutral contact 15 of relay H' closes the clear indication circuit for signal S' which circuit is as follows—from battery D' through wires 13 and 14, contact 15, polarized contact 16, wire 17, operating mechanism for semaphore 95 arm 11, wire 18, contact 19, wire 62, to battery D'. Semaphore arm 11 therefore moves to "clear" position as indicated in Fig. 2. The closing of the neutral armature of relay H closes the following circuit to energize auxiliary relay R—from battery D through wires 35 and 36, contact 37, polarized contact 38, wire 39, winding of relay R, wire 40, contact 41, wire 20, to battery D.

The closing of relay R closes a branch 110

around a portion of the line circuit hereinbefore traced, which branch is from wire 71, through wire 32, contact 33, wire 34, to wire 20. It will be seen that this branch is in parallel with contact 24 of relay P, hence if, 5 while the car or train W occupies preliminary track circuit p' an east-bound car or train should enter preliminary section p , the opening of track relay P would have no effect on the line circuit and consequently 10 would not open the circuit of semaphore 11 of signal S'; neither would it close the circuit for either the clear or caution indication of signal S hence this east-bound car or train would be held in track circuit p . 15 While the semaphore arm 11 of signal S' is in clear position a pick-up circuit for relay L' is closed which circuit is as follows: from battery D' through wire 13, contact 42, wire 43, winding of relay L', wires 44 and 62 to battery D'. Relay L' therefore closes. 20 When the car or train W enters the stretch A, as shown in Fig. 3, the opening of track relay T' opens the line circuit, thereby de- 25 energizing relays H' and H. The opening of contact 15 and reversal of contact 16 of relay H' opens at two places the circuit of semaphore 11 which then returns to horizontal position, but before contact 42 has 30 opened, the closing of back contact 60 of relay H' closes the following holding circuit for relay L'—from battery D' through wires 13 and 14, contact 60 of relay H', wire 46, contact 47, wire 45, winding of relay L', wires 44 and 62, to battery D'. Relay L' is held closed by this stick circuit. The 35 opening of relay H opens the circuit of relay R, which relay is thereby deenergized. The opening of track relay T' also closes 40 relay R' through the following circuit—from battery D' through wires 13 and 63, contact 64, wire 65, winding of relay R', wire 66, contact 41, wire 62 to battery D'. The opening of this relay T' has however 45 no effect on the operation of the rest of the apparatus.

As the car or train W passes the middle of stretch A and deenergizes track relay T, 50 as shown in Fig. 4, it has no effect on the line circuit other than to open this circuit at another point, that is, at contact 28 of relay T. The opening of track relay T, however, again energizes relay R through 55 the following circuit—from battery D through wires 35 and 53, contact 54, wire 55, winding of relay R, wire 40, contact 41, wire 20 to battery D. Relay R therefore closes. As the car or train W enters preliminary section p , as shown in Fig. 5, the 60 opening of track relay P closes a holding circuit for relay R as follows—from battery D, through wire 56, contact 57, wire 58, contact 59, winding of relay R, wire 65, contact 41, wire 20, to battery D. Hence,

when the entire car or train has left the stretch A and occupies preliminary section p the line circuit for the control of signal S will not be closed because relay R is closed and the line circuit is therefore held open at 70 contact 22 of this relay. Consequently signal S will not be affected.

It will be noted that after the passage of a car or train through the stretch from east to west as just explained, relay L' re- 75 mains closed. When now a following west-bound car or train enters preliminary section p' it opens relay P', which latter causes relay H' to close. The closing of relay H' opens the holding circuit for relay L', and 80 closes the circuit for arm 11 of signal S'.

The operation of the apparatus during the passage of an east-bound car or train is similar to that just explained. In this case, relay R would be open, so the opening 85 of track relay P by a car entering section p would close the following line circuit—from battery D through wires 67 and 68, contact 22, wire 69, contact 24, wires 72 and 71, winding of relay H, wire 70, contact 28 90 of relay T, wire 29, contact 28 of relay T', wire 27, winding of relay H', wires 26 and 25, contacts 24 of relay P', wires 62 and O to battery D. If relay L' has been left closed by a west-bound car or train it will 95 now be opened by the closing of the neutral armature of polarized relay H'. Current in the line circuit just traced is in such direction as to reverse the polarized armature contact of relay H, but to not reverse that 100 of relay H'. Hence if the stretch A and preliminary section p' are unoccupied, arm 11 of signal S will be cleared and the car may proceed through the stretch. Further explanation of the operation of the apparatus for movement in this direction is unnecessary. 105

If, with the car or train W in the stretch A as shown in Figs. 3 or 4, a following car or train moving from east to west should enter preliminary section p' , the caution semaphore arm 12 would be cleared for the following reason: The opening of track relay P' could not close the line circuit because this circuit would be held open by 115 either track relay T' or T. Relay L' is however already closed, so the following circuit for semaphore 12 would be closed—from battery D' through wire 48, contact 49, wire 50, contact 51, wire 52, operating mechanism 120 for semaphore arm 12, wire 18, contact 19, wire 62 to battery D'. Arm 12 therefore clears, so the following car or train could then enter the stretch A under caution expecting to find a preceding car or train in 125 the stretch. As soon as the following car or train leaves the preliminary section p' track relay P' closes thereby opening the circuit just traced for semaphore arm 12, hence this arm returns to horizontal position. 130

If, while the car or train W occupies preliminary section p' or stretch A, as shown in Figs. 2, 3 and 4, an east bound car or train should enter preliminary section p , it would be brought to a stop because it could not cause signal S to clear. The switch 61 would then be opened to permit a car or train W to enter siding B and the opening of this switch would open contact 41, which latter would hold open relay R when the car or train W is in the west end of stretch A. As soon as the entire car or train W has entered siding B track relay T would close and the car or train occupying preliminary section p would then cause the line circuit to be closed so that semaphore 11 of signal S would move to clear position.

Although I have herein shown and described only one form of railway signaling embodying my invention, it is understood that various changes and modifications may be made therein within the scope of the appended claims without departing from the spirit and scope of my invention.

Having thus described my invention, what I claim is:—

1. In combination, a stretch of railway track over which traffic moves in both directions; a signal device adjacent each end of the stretch for governing traffic through the stretch and adapted to indicate stop, caution and clear, a clear indication circuit and a caution indication circuit for each signal device, a polarized relay adjacent each signal device each having a polarized armature for the control of the clear indication circuit and each having a neutral armature, a normally closed line circuit extending through the stretch and including the windings of the two polarized relays; means controlled by the presence of a train in the stretch for holding the line circuit open, and means controlled by a train approaching the stretch from either direction for sending current through the line circuit in one direction or the other according to the direction from which the train is approaching, the polarized relays being so connected in said line circuit that current flows through one of them in the effective direction and through the other in the ineffective direction at the same time, a circuit controller operated by each signal device, and closed only when the signal device indicates clear, a caution relay for each signal device for the control of the caution indication circuit thereof, a pick-up circuit for each caution relay including the said circuit controller operated by the adjacent signal device, and a holding circuit for each caution relay including a front contact of such caution relay and a back contact of the neutral armature of the adjacent polarized relay.

2. In combination, a stretch of railway track, a signal device located adjacent each

end of the stretch for governing traffic through the stretch, each signal device being adapted to indicate stop, caution and clear, a polarized relay for each signal device for controlling the clear indication thereof, a line circuit extending through the stretch and including the windings of said polarized relays, means controlled by a train approaching the stretch from one direction or the other for sending current through said line circuit in one direction or the other, said polarized relays being so connected in said circuit that the current through one of them is in an effective direction and through the other in an ineffective direction at the same time, means controlled by a train in the stretch for opening the line circuit, a caution relay for each signal device for controlling the caution indication thereof, and means for closing each caution relay when a train enters the stretch from the corresponding end and for holding said caution relay closed while the train occupies the stretch, said caution indication being also controlled by the said means controlled by a train approaching the stretch.

3. In combination, a stretch of railway track, a signal device located adjacent each end of the stretch for governing traffic through the stretch, a polarized relay for each signal device for the control thereof, a common wire extending through the stretch, a source of current adjacent each end of the stretch the same pole of each source being connected with said common wire, a line wire extending through the stretch and connected with one terminal of each polarized relay, a preliminary track circuit adjacent each end of the stretch and including a track relay, contacts and conductors controlled by each track relay for connecting the remaining terminal of the adjacent polarized relay with the common wire or with the remaining pole of the adjacent source of current, the polarized relays being so connected with said line wire that the current flows through one of them in the effective direction and through the other in the ineffective direction at the same time, means controlled by a train in the stretch for deenergizing said polarized relays; an auxiliary relay adjacent each end of the stretch for opening the connection between the source of current and the polarized relay, and means controlled by each polarized relay when energized in the non-effective direction for operating the adjacent auxiliary relay to open the connection controlled thereby.

4. In combination, a stretch of railway track, a signal device located adjacent each end of the stretch for governing traffic through the stretch, a polarized relay for each signal device for the control thereof, a common wire extending through the stretch; a source of current adjacent each end of the

- stretch the same pole of each source being connected with said common wire, a line wire extending through the stretch and connected with one terminal of each polarized relay, a preliminary track circuit adjacent each end of the stretch and including a track relay, contacts and conductors controlled by each track relay for connecting the remaining terminal of the adjacent polarized relay with the common wire or with the remaining pole of the adjacent source of current, the polarized relays being so connected with said line wire that the current flows through one of them in the effective direction and through the other in the ineffective direction at the same time, means controlled by a train in the stretch for deenergizing said polarized relays; an auxiliary relay adjacent each end of the stretch for opening the connection between the source and the polarized relay, and for bridging the track relay contact which connects the polarized relay with the common wire, and means controlled by each polarized relay when energized in the non-effective direction for causing operation of the adjacent auxiliary relay.
5. In combination, a stretch of railway track, a signal device located adjacent each end of the stretch for governing traffic through the stretch, a polarized relay for each signal device for the control thereof, a common wire extending through the stretch, a source of current adjacent each end of the

stretch the same pole of each source being connected with said common wire, a line wire extending through the stretch and connected with one terminal of each polarized relay, a preliminary track circuit adjacent each end of the stretch and including a track relay, contacts and conductors controlled by each track relay for connecting the remaining terminal of the adjacent polarized relay with the common wire or with the remaining pole of the adjacent source of current, the polarized relays being so connected with said line wire that the current flows through one of them in the effective direction and through the other in the ineffective direction at the same time, track circuits for the stretch including track relays for controlling said polarized relays; an auxiliary relay adjacent each end of the stretch for opening the connection between the source of current and the polarized relay, and means controlled by the track relays for operating each auxiliary relay as a train passes out of the stretch at the adjacent end and for continuing the operation of the relay while the train occupies the preliminary section.

In testimony whereof I affix my signature in presence of two witnesses.

RONALD A. McCANN.
